US0D1077647S

(12) **United States Design Patent** (10) **Patent No.:** **US D1,077,647 S**
(45) **Date of Patent:** **** Jun. 3, 2025**

(54) **TRAY**

(71) Applicant: **MARS, INCORPORATED**, McLean, VA (US)

(72) Inventors: **Jonathan Lee McSweeney**, Antioch, TN (US); **Jonathan Christopher Smith**, Nashville, TN (US)

(73) Assignee: **MARS, INCORPORATED**, McLean, VA (US)

(**) Term: **15 Years**

(21) Appl. No.: **29/830,916**

(22) Filed: **Mar. 16, 2022**

Related U.S. Application Data

(62) Division of application No. 29/662,602, filed on Sep. 6, 2018, now Pat. No. Des. 950,395, which is a (Continued)

(57) **CLAIM**

The ornamental design for a tray as shown and described.

DESCRIPTION

FIG. 1 is a perspective view of a tray showing our new design;

FIG. 2 is a top view of the design shown in FIG. 1;

FIG. 3 is a bottom view of the design shown in FIG. 1; FIG. 4 is a right side view of the design shown in FIG. 1, wherein the left side view is a mirror image to the view in FIG. 4; and,

FIG. 5 is a front view of the design shown in FIG. 1; wherein the rear view is a mirror image to the view in FIG. 5.

The broken lines illustrate portions of the tray and form no part of the claimed design.

1 Claim, 4 Drawing Sheets

Related U.S. Application Data

division of application No. 29/606,296, filed on Jun. 2, 2017, now Pat. No. Des. 831,505, which is a division of application No. 29/505,762, filed on Feb. 2, 2016, now abandoned, which is a division of application No. 29/463,739, filed on Feb. 21, 2014, now Pat. No. Des. 750,973.
